[57] CLAIM

The ornamental design for a spindlecage attachment for tapping machines to change the rotation of the tool, substantially as shown.

DESCRIPTION

FIG. 1 is a top plan view of a spindlecage attachment for tapping machines to change the rotation of the tool showing my new design;

FIG. 2 is a bottom plan view thereof;

FIG. 3 is a front elevational view thereof;

FIG. 4 is a side elevational view taken from the left of

FIG. 3;

FIG. 5 is a rear elevational view thereof;

FIG. 6 is a side elevational view taken from the right of FIG. 3.

FIG. 1.

FIG. 2.

FIG. 3.

FIG. 4.

FIG. 5.

FIG. 6.
